By his Attorneys,

Inventor:

 a. M. Dunn

C. A. Howes Co.

UNITED STATES PATENT OFFICE.

ALFRED MORRISON DUNN, OF PLEASANT HILL, MISSOURI.

CHURN.

SPECIFICATION forming part of Letters Patent No. 367,797, dated August 9, 1887.

Application filed May 4, 1887. Serial No. 237,124. (No model.)

To all whom it may concern:

Be it known that I, ALFRED MORRISON DUNN, a citizen of the United States, residing at Pleasant Hill, in the county of Cass and 5 State of Missouri, have invented a new and useful Improvement in Churns, of which the following is a specification.

My invention relates to improvements in churns; and it consists in a certain novel construction of parts for service, fully set forth hereinafter, and specifically pointed out in the claim.

In the accompanying drawings, Figure 1 is a front view of a churn embodying my improvements, with the tub or churn-body shown in section. Fig. 2 is a side view of the same. Figs. 3 and 4 are detail views. Fig. 5 is a detail section on the line xx of Fig. 1. Fig. 6 is a partial rear view of the churn-operating 20 mechanism to show the ear formed on the rear supporting-bar.

Referring to the drawings by letter, A designates a collar or band adapted to fit around the upper edge of the churn-body B, and C C D 25 are standards bolted at their lower ends to the said collar and bent inwardly at the upper ends and secured together, a vertical bearing being formed at the intersection of the said standards to align with a bearing in the lid of 30 the churn.

E designates a journal, bolt, or spindle, formed integral with the standard D at its upper end and projecting forwardly therefrom, and on the said spindle is journaled the driving-wheel G, having the gear-teeth g on the rim and the teeth g' on the rear side thereof, 35 near the periphery, a suitable handle, H, being attached to the said wheel to operate the same.

I represents a vertical dasher-shaft journaled in an opening in the churn-lid and the upper part of the frame.

I' is a pinion secured on the upper end of the shaft to mesh with the side gear-teeth, g' , 45 of the power-wheel G, and I'' is a revolving dasher secured to the lower end of the said shaft. At an intermediate point of the said dasher-shaft is arranged a coupling, i , in which an angular stud, i' , on the end of one portion 50 of the shaft enters an angular recess or socket, i'' , in the end of the other portion of the shaft,

and is secured therein by the pin i^3 , which is passed therethrough, whereby, when the said pin is drawn out, the dasher will drop into the churn.

K represents a cross-brace extended between the side standards, C C, and in aligned bearings in the said brace; and in the lateral ear K', on the side of the standard D, is journaled the horizontal crank-shaft L, to the outer end of 60 which is attached the pinion L', which meshes with the rim-teeth g of the wheel G.

M is a circular vertically - reciprocating dasher having a central opening therein, forming a bearing whereby it may slide on 65 the shaft I, and to the said dasher is secured the vertical bar N, which passes up through an opening in the cover of the churn, and is pivotally connected to the lower end of the connecting-link O, the upper end of which is 70 journaled on the crank of the shaft L, so that when the said shaft is rotated by means of the pinion on the end thereof the bar N will be vertically reciprocated.

The pivot-pin n , which passes through the 75 upper bifurcated end of the bar N and the lower end of the connecting-link O to pivotally secure the said members together, is adapted to be withdrawn to allow the dasher attached to the said bar N to drop into the 80 churn.

The operation of my improved churn will be readily understood from the foregoing description.

When the power-wheel is rotated the vertical dasher-shaft I is rotated, thereby rotating the dasher I', attached thereto, and at the same time the vertically-reciprocating dasher M is operated by means of the crank-shaft bar and connecting-rod, hereinbefore described, thus 85 violently agitating the contents of the churn-tub. When the churning has been completed, the pins n and i^3 are withdrawn, the dashers thus being dropped into the tub, and the upper part of the churn, or all of the operating 95 mechanism, is lifted off, thus allowing the churn-tub to be easily reached to clean the said dashers.

The improved churn will be found very strong, durable and effective, and easy to operate.

Having thus described the construction and

operation of my improved churn, what I claim, and desire to secure by Letters Patent of the United States, is—

In a churn, the collar A, standards C C D, secured at their lower ends thereto and secured together at their upper ends, spindle E, formed integral with the standard D at the upper end, cross-brace K, between the standards C C and the ear K' on the side of the standard D, combined with the vertical shaft I, having the pinion I' on the upper end and the dasher I² on the lower end, power-wheel G, journaled on the said spindle E, and having the teeth g and g' thereon, crank-shaft L, journaled in bearings

in the said cross-brace K and the ear K', and 15 having the pinion L' thereon, bar N, and the connecting-link O, attached to the said shaft L and the bar N, and the dasher M on the lower end of the bar N, all constructed and arranged substantially as specified. 20

In testimony that I claim the foregoing as my own I have hereto affixed my signature in presence of two witnesses.

ALFRED MORRISON DUNN.
